DESIGN FOR A DESK ORNAMENT

Noel Meadow, New York, N. Y.

Application December 30, 1944, Serial No. 117,184

Term of patent 3½ years

(Cl. D74—1)

To all whom it may concern:

Be it known that I, Noel Meadow, a citizen of the United States, residing at New York, in the county of New York and State of New York, have invented a new, original, and ornamental Design for a Desk Ornament, of which the following is a specification, reference being had to the accompanying drawing, forming part thereof.

I claim:

The ornamental design for a desk ornament, substantially as shown.

NOEL MEADOW.
